UNITED STATES PATENT OFFICE

ALAN C. HOOVER, OF CHICAGO, ILLINOIS

MACHINE FOR FORMING ARTICLES

Application filed March 28, 1929. Serial No. 350,482.

This invention relates to a machine for forming an article; and more particularly to a machine for imparting an accurate circular form or curvature to a rotary contact element of an electric switch, or a similar thin metal article.

It has been the practice heretofore to form such a rotary contact element, and similar metal elements or articles, either by hand or 10 else by the punch and die method and then to perfect it by hand after assembly; in either case involving considerable time and labor and becoming expensive for such small articles, and still not imparting the complete 15 and accurate circular form as required.

It is the principal object of this invention to provide a machine for imparting an accurate and complete circular form or curvature to a rotary contact element of an electric 20 switch and to similar elements or articles, without any aid from the usual manual method or the punch and die method. Another object is to provide such a machine having 25 means for guiding the element and for advancing and curving it, and adjustable means to provide for different degrees of curvature and to compensate for different thicknesses of the elements. A further object is to provide such an element curving or forming machine 30 which is simple and sturdy in construction, economical in manufacture, and is readily operated for speedily forming the element.

These and other objects and advantages 35 are attained with this invention, as will become apparent from the following description, taken in connection with the accompanying drawings, in which

Fig. 1 is a plan view of my novel machine.
Fig. 2 is a side elevation thereof.

Fig. 3 is a detail vertical section on line 3—3 of Fig. 2.

Fig. 4 is a cross-section on slanting line 4—4 of Fig. 2.

Fig. 5 is a vertical section on line 5—5 of Fig. 1.

Fig. 6 is an elevation of an element in its unbent form.

Fig. 7 is an elevation of said element after

the circular form has been imparted thereto by my machine.

Fig. 8 is an inverted plan view of said element.

The drawings illustrate an embodiment of 55 my invention in its preferred form of construction, comprising a frame 10 having lower supporting flanges 11, and a top plate or head plate 12 removably mounted on its upper end, as with screws 13.

The machine illustrated herein is shown as arranged for imparting circular form or curvature to a rotary contact element 14 of an electric switch; and the means shown herein for guiding this switch element during the 65 curving operation comprises the head plate 12 which has a guide channel or furrow 15 provided in its front part, and a guide plate 16 which has a straight lower face for providing, with said channel 15 in plate 12, a 70 right-line guide channel or straight guide means, to guide the element 14 which is originally straight, as illustrated in Fig. 6.

Since this particular switch element 14 has fingers or lips 17 extending downwardly 75 and outwardly from its ends, the guide means is provided with grooves, preferably with grooves 18 extending longitudinally of channel 15 in plate 12, to accommodate said fingers; and this plate 12 is replaceable by a 80 suitably grooved one, if necessary, for guiding a different shaped element. Guide plate 16 is adjustably mounted on plate 12, as by screws 19 and slots 20 provided in plate 16 wherein said screws adjustably engage, so 85 that said plate may be adjusted in accordance with the particular degree of curvature or selected form desired to be imparted to the element.

Means is provided for advancing or drawing the element or article through the guide means and for imparting the selected form or curvature thereto, and this means preferably comprises a pair of adjoining rotary members for clamping the element therebetween and advancing and shaping it. These members are preferably made in the form of a pair of rollers 21 and 22 which have their cylindrical surfaces substantially contacting and are mounted to have the line of 100

contact extend cross-wise of the guide channel, and slightly forward and downward of the lower front end 24 of plate 16 and its guide face. Rollers 21 and 22 are provided with intermeshing gears 25 and 26 to rotate in unison; and in the illustrated machine this roller 22 is provided with grooves 22' corresponding with groove 18 in plate 12, to accommodate fingers 17 on this type of element 14.

Means is provided for supporting the rollers 21 and 22, and means for adjusting the supporting means and rollers, in conjunction with the adjusting of the guide plate 16, for the purpose of imparting to the elements the particular degree of curvature or circular form desired. This supporting means preferably comprises an inner or upper supporting member or yoke 27, and an outer or lower supporting member or yoke 28 having its upstanding yoke arms engaging in grooves 29 provided on the outside of the upstanding arms of yoke 27. A shaft 31 extends through inner yoke 27 and has the roller 21 and the attached gear 25 rotatably mounted thereon, as with a bushing or bearing 30. A drive shaft 32, which is driven by any suitable power supplying means, extends through bearings 33 provided in the upper part of frame 10, extending further through the arms of outer yoke 28, through enlarged openings 34 in the arms of the inner yoke 27, and through roller 22 and attached gear 26. Said shaft 32 is fastened to roller 22, as with a set screw 35, for driving the rollers.

The means for adjusting and holding the supporting means or yokes 27 and 28 with their rollers 21 and 22 in the proper positions, comprises a bolt 36 secured to the outer yoke 28 and movable in a curved slot 37 provided in the side of frame 10, for swinging the yokes and their rollers upon drive shaft 32 as a pivot. A nut 38 on the outer end of the bolt is then tightened, after the yokes and rollers have been set in the proper position, to retain them therein for imparting the desired degree of curvature or circular form to the particular element.

Means is also provided for compensating for differences in the thickness of the elements or articles to be curved, and said means preferably comprises a bolt or shaft 40 mounted in the inner yoke 27 and extending slidably through the outer yoke 28, also a spring 41 mounted on said bolt outside of yoke 28 and a nut 42 adjustable on the lower end of said bolt to adjust the tension of said spring, for resiliently and adjustably urging and holding the rollers close together or in contact.

It should be observed that yoke 27 has a sliding movement in yoke 28, permitted by grooves 29 and enlarged openings 34 in the arms of yoke 27; and that by the proper adjusting of nut 42, the spring 41 with bolt 40

will firmly but resiliently hold the upper roller 21 close to the lower roller 22, to clasp and advance the element 14 therebetween, and also to compensate for any irregularities in the thickness on any element and for the differences in the thicknesses of the various elements.

It should also be observed that the shafts 31 and 32 and the rollers 21 and 22 are mounted so that their axes extend cross-wise of the guide plate 16 and guide channel thereunder; and that a plane passed through said axes will be at an angle with a vertical line and adjacent the front end 24 of plate 16; these rollers being thereby so positioned that said front end of plate 16 is at or adjacent the uppermost line or part α of the lower roller 22, being spaced or separated thereabove only by the thickness of element 14, and the line γ of closest junction or contact between the rollers being lower and forward of said uppermost line α ; whereby the curvature or circular form is imparted to the element during its movement from said line α to line γ , over the curved upper portion of the lower roller 22. It is also apparent that by operating nut 38 and bolt 36 and adjusting the supporting yokes thereby, so that the upper roller 21 is placed further forward; that the junction line γ between the rollers is placed further downward and away from the top line α on the lower roller; and that thereby a more prolonged bending action is exerted upon the element and a greater degree of curvature or more contracted circular form is imparted thereto. It is further apparent that by adjusting guide plate 16 further backward, and by adjusting the upper roller 21 further backward and upward, so that the plane passing through the axes of the rollers is nearly vertical, a very slight bending effect and degree of curvature or circular form can be imparted to the element.

Although the preferred form of my invention only is disclosed herein, I do not purpose limiting the patent granted thereon, except as necessitated by the prior art.

What I claim as my invention and desire to secure by Letters Patent is:

1. A machine for imparting circular form to an element, comprising means for guiding the element, supporting means having rollers therein for advancing and curving the element, and spring actuated means for adjusting and moving one of said rollers and its supporting means with respect to the other roller and its supporting means to compensate for various thicknesses of the elements.

2. A machine having a removable head plate and a guide plate adjustably mounted thereon and providing therewith a guide channel for guiding an element, supporting means having shafts with rollers thereon which substantially contact for drawing said element from said channel, a plane through

the axes of said shafts forming an angle with a plane through said channel, and means for adjusting said supporting means and rollers to vary said angle, for imparting various degrees of curvature to the elements.

5 3. A machine comprising a head plate having a guide plate adjustably mounted thereon and providing therewith a guide channel for guiding an element, rollers and supporting means therefor mounted at the front of 10 said plates and channel, one of said rollers being positioned closely beneath the front end of said guide plate and the other roller being positioned forwardly and upwardly of said plate end, and means for adjusting said rollers with their supporting means and said guide plate, for varying the degree of curvature imparted to the element by its travel from said channel and between said rollers.

15 4. A machine comprising plate means for 20 guiding an element, a supporting yoke having a drive shaft and a roller therein, a second supporting yoke having a shaft and roller therein and being therewith movable on the first yoke, means for adjustably and resiliently holding the rollers in contact, and means for adjustably holding said yokes and rollers in position to have the lower roller closely beneath the end of the said plate means and 25 to have the other roller forwardly and upwardly of said end, for imparting circular form to the element and to vary said form.

30 5. A machine comprising plate means providing a guide channel having grooves therein, a yoke with a drive shaft and a roller, an 35 inner yoke carrying a shaft and an upper roller, there being grooves on one of said rollers to correspond to the grooves in said channel to accommodate offset fingers on an element to be curved in said machine, said 40 plate means being removable and replaceable to suit the shape of the element, and means for adjustably holding said rollers for drawing the element from the channel and imparting a complete circular form thereto.

45 In testimony whereof I have signed my name to this specification.

ALAN C. HOOVER.
